19 Claims. (Cl. 93—2)

1

This invention relates to machines for packeting cigarette papers and like articles of a relatively flat nature. More particularly stated the invention concerns such machines of the kind comprising an intermittently moving conveyor bearing uniformly spaced pockets within which suitable card blanks are fashioned into shallow cartons or packets then filled with the articles to be packed and subsequently closed and sealed before being discharged from the pocket, the conveyor sustaining the pocket devices adjacent suitable devices all forming part of the machine for performing the said operations in proper sequence.

In certain known machines for packeting cigarette papers it has been the practice to fashion the carton by pressing the blank into an open bottomed pocket from which after the subsequent operations have been performed, it is finally ejected upwardly, the leading edge of the first leaf of the cigarette paper booklet, in the case of interleaved cigarette papers, being withdrawn through a slotted opening in the package by means of a suction device operating from beneath the open bottomed pocket. This operation taking place as it does on the underside of the pocket, is not under the direct observation of the machine attendant who may thus inadvertently permit defective work to pass from the machine. Moreover the extracted leading edge of the leaf is liable to be disarranged or torn during the subsequent movements of the packets to the ejection station.

The primary object of the present invention is to provide an improved machine of the kind indicated which will be readily adjustable for making and filling packets of different sizes. A further object of the invention is to provide means whereby such a machine may be readily adapted to pack either one booklet per packet as in the so-called "singles" packets, or to pack two booklets per packet as is required in the so-called "doubles" packet. A still further object of this invention is to provide in such a machine means whereby the withdrawal of the leading edge of the first leaf may be performed in full view of the machine attendant and without risk of said leaf suffering disarrangement due to subsequent movements in the machine.

The improved packeting machine forming the subject matter of the present invention comprises an intermittently moving chain conveyor running lengthways of the machine immediately beneath two laterally spaced guide bars and the pockets within which the packets are fashioned and filled

2

are constituted partly by platforms attached to the conveyor and furnished with ledges towards the forward and rearward edges and partly by the said spaced guide bars. The ledges furnished on the platforms are adjustable in relation to one another and the spaced guide bars can also be moved relatively one to another to enable the pockets to be adapted to the size of the packets to be made and filled. The spaced guide bars extend substantially throughout the length of the machine to the packet ejection point and are thus able to support the side walls of the packet as it is pressed to shape and as it moves along the bed of the machine to the stations where the folding and gumming operations are performed. The ledges furnished on the platforms are undercut on the inside so as to form recesses into which the end walls of the packet may be pressed as herein-after explained.

20 In the sequence of operations the card blank from which the packet is to be formed is taken from a stack by any known means such as suction operated devices and positioned over a pocket on the conveyor and immediately beneath a 25 plunger which descends to press the blank into the said pocket. The blank feeding means may either be of the type which feeds blanks from the top of a stack or alternatively the continuously fed type wherein the blanks are taken from the bottom of the stack, and thence conveyed to the plunger mechanism.

This plunger mechanism comprises three main parts sliding one within another. The innermost part is adapted to carry at opposite ends, two 35 hinged pawls or wings so arranged that when the plunger descends to the bottom of its stroke, the pawls or wings splay outwardly slightly (the amount being adjustable) thus forcing the formed corner of the end walls of the plunged blank 40 into the aforementioned recesses at the bottom of the end walls of the conveyor pocket. When the plunger returns on its stroke these pawls or wings retract to their original dimension—roughly equivalent to the inside dimensions of 45 the packet—thus permitting the plunger to withdraw freely.

The innermost member referred to, carrying the aforesaid pawls or wings is adapted to slide within a second or "forming" member, the side 50 walls of which correspond approximately to the inside dimensions of the packet and which is arranged to be sprung pressed downwardly. The function of this "forming" member is to do the main plunging operation and to hold the blank 55 when plunged whilst the pawls are acting to push

outwardly the end walls of the packet as described.

The third or outermost member is free to slide over the "forming" member and is for the purpose of opening out to the required degree the upstanding flaps of the plunged blank for the purpose later on of receiving the contents.

The purpose of this arrangement of the plunger is to splay outwardly slightly the bottom panel of the packet to ensure that it will not spring out again from the pocket after plunging—a tendency which exists due to the shallow depth of the packet and the natural springiness of the card or paper material used.

After plunging, the cover is conveyed to appropriate stations to receive the booklet or other contents and for subsequent folding and gumming operations.

The booklets are arranged to be fed from one side of the machine towards the centre, in the case of the "singles" packing, and from both sides of the machine in the case of the "doubles" packing. In the "doubles" packing it will be understood that the booklets lay side by side in the packet. In the case of the "singles" packing it is necessary to use only one booklet feed. The second feed required for the "doubles" packing is arranged to be bolted on the opposite side of the bed and is coupled to the first feed, and takes its drive from the same. The feed, when a "singles" booklet is required, can be adjusted immediately over the centre line of the conveyor pockets.

The feeding forward of the booklets towards the centre of the machine can be by any known means such as a belt conveyor and the booklets are delivered to a platform arranged on the centre line of the machine and situated just above the conveyor pockets. The booklets are removed from the platform by means of a pusher which reciprocates in the direction of the conveyor pocket and delivers the booklet (or booklets) in the case of the "doubles" feed, into the plunged cover which has previously passed beneath the platform and is in position to receive same.

This pusher, which is driven forward positively by a cam and spring-returned on to its cam, is arranged to be prevented from returning by means of a pin which is brought into its path in the event of the next succeeding conveyor pocket containing no prepared cover.

A detecting finger is arranged to be spring pressed through an aperture in the guide bar on to the cover, if present. If the cover is absent, the increased movement of the finger due to the absence of the cover brings the aforesaid pin into the path of the pusher mechanism and prevents the pusher from returning, so missing one cycle of the feeding operation of the pusher, and ensuring that the empty pocket does not receive a booklet. The next cycle of operations releases the pin and, provided a cover is present in the next pocket, the pusher resumes its travel and the supply of booklets.

After the subsequent folding and gumming operations which form no part of the present invention the pocket arrives opposite a pusher arranged on the side of the machine bed and operating transversely to the main pocket conveyor. This pusher ejects the filled, tucked and partly folded packet into a receiver which is arranged vertically and to rotate intermittently, through an angle of 90°, by means, preferably, of a "Geneva" drive wheel or the like.

The first stage in the rotation of this receiver

exposes in a vertical position the underside of the packet with its slot opening for the extraction of the interleaved contents.

Whilst in this vertical position, a suction chamber carried on an arm is arranged to swing into position to partially withdraw the first leaf in the usual manner. This suction chamber is provided with either one or two nozzle openings as required according to whether a "singles" or a "doubles" packet is being operated upon.

The subsequent rotation movement of the receiver is used to partially fold over the still upstanding flap of the packet and during the dwell period the packet is ejected horizontally out of the receiver away from the machine and delivered on to a plate or platform where the packet receives a final pressing through a cam mechanism. During this ejection the final folding over of the flap is accomplished.

The packet remains on this platform until the ejection of a subsequent packet which pushes the preceding one into a stacker where it is collated on edge for collection.

This invention is hereinafter more fully described with reference to the accompanying drawings wherein—

Figure 1 is a longitudinal side elevation partly in section of a machine constructed in accordance with this invention certain parts being omitted for the sake of clarity.

Figure 2 is a plan view of the same.

Figure 3 shows in sectional elevation on an enlarged scale the three part plunger used for forming the packets.

Figures 4, 5 and 6 are detail views illustrating the mechanism employed in feeding single booklets to the formed packages.

Figure 7 is a section on the line 7—7 shown in Figure 2 illustrating the receiver mechanism where the final folding operations and the collating of the finished packets takes place.

Figures 8 and 9 are plan views of card blanks adapted for use in the making of "singles" and "doubles" packets respectively.

Figure 10 is a detail perspective showing the relation of a conveyor plate with adjacent guides to form a packet receiving pocket.

Referring to these figures it may be seen that the machine here considered comprises an endless chain 1 arranged longitudinally of the machine frame and running over sprocket wheels 2 and 3. Rotary motion imparted to a drive wheel 4 on a shaft 5 at one end of the machine is transferred through gear wheels 6 and 7 to a further shaft 8 extending along the length of the machine and bearing at intervals drive wheels and cams for operating the various component parts of the machine. At its remote end the shaft 8 is operatively connected through bevel wheels 9, 10 and spur wheels 11, 12 to a crank 13. This crank is associated with a slide bar 14 which slides in a slot in a boss 15 loose upon the shaft of the wheel 3. The wheel 3 is formed with a laterally projecting rim 16 which is slotted at regular intervals and a feather 17 on the side of the slide bar 14 is arranged in the course of the rotation of the crank 13 to engage in one of the slots in the rim 16 and turn the wheel 3 by an amount equal to the interval between the spaced slots. Operating alternately with the slide bar 14 is a locking lever 18, 19 arranged to be actuated by a cam attached to the wheel 12, the lever 19 bearing at its end a detent 20 which by engagement in the slotted rim 16 locks the wheel 3 in the intervals between the turning movements

induced by the slide bar 14. This method of imparting to the endless chain an intermittent drive enables a relatively high speed of operation being attained without the mechanism overshooting its appropriate positions of rest.

Attached to the endless chain 1 at regular intervals are a series of platforms 21 having secured at their forward and rearward ends undercut ledges 22 the spacing between which can be adjusted to suit the size of the packets to be made and filled. While traversing the upper run of the chain 1 these platforms pass immediately beneath a pair of laterally spaced guide plates 23 extending longitudinally of the machine these plates also being adjustable towards or from one another to enable the machine to be adapted for dealing with "singles" packets or "doubles" packets as required. In the illustrations referred to these guide plates are spaced as required for dealing with "singles" packets. The platforms 21 and the guide plates 23 serve between them to support the packets not only while they are being formed but also during the filling, gumming and folding operations.

The platforms 21 on arriving at the right hand end of the upper run of the endless chain (as seen in Figure 1) pause beneath a plunger device shown in Figure 3 and at this position a cut blank 24 suitable for the making of a packet is fed by suitable known means to a position overlying the "pocket" constituted between the ledges 22 on the said platform and the guide plates 23. Immediately following this operation the plunger A shown in Figure 3 situated in vertical alignment with the said pocket is caused to descend and to plunge the body portion of the blank into the said pocket.

In order to appreciate the nature of the packets being made and filled by this improved machine reference may be had to Figures 8 and 9 wherein card blanks for making "singles" and "doubles" packets of cigarette booklets are shown in plan, the lines whereon the various folds occur in the making of the packet being shown as dotted lines. Each blank comprises a rectangular front panel *a* having a longitudinally arranged slot *b* through which the cigarette papers may be withdrawn. Extending integrally from the margins of this front panel are four wings or flaps which assist in the make up of the packet. Thus there are two end flaps *c* the root portions *c'* of which constitute the end walls of the packet. In addition there are two side wings *d* and *e* the root portions *d'* and *e'* of which form the side walls of the packet while the terminal parts *c*, *d* and the wing part *e* are arranged on being folded and gummed together to form the back wall of the packet. The wing part *e* is also extended further at *f* to furnish an outer flap for protecting the delivery slot *b*. The blank shown in Figure 9 is proportionately larger whereby it may form a packet containing two booklets of cigarette papers and its front panel has two delivery openings *b*. In some cases it may be preferred to dispense with the gumming apparatus in which event the blanks will be furnished with two additional flaps as those shown in chain dotted lines at *g* in Figure 8, these being provided to enable the package to be secured in a known manner by a tucking-in operation.

The plunger A previously referred to is composed of three main parts arranged to operate as hereinafter stated in fashioning the required package. The innermost part 25 of the plunger is arranged to carry two hinged pawls 26 acted

upon by a spring 27 in such a way that their free ends are splayed downwardly and outwardly towards the leading and rear ends of the plunger. As the plunger is pressed downwardly in forming a packet these pawls on encountering the bottom of the pocket force the end walls of the packet into the undercut portion of the ledges 22 and thereby not only impart a "set" to these walls but cause the formed packet to remain in position on the platform throughout subsequent operations on the machine as hereinafter explained. When the plunger ascends after performing its operation these pawls 26 retract to a normal situation permitting them to clear the walls of the packet as the plunger is withdrawn.

About the innermost member 25 is provided a second or a packet forming member 28 having side and end walls 29 corresponding approximately to the internal dimensions of the package to be made. This packet forming member is pressed downwardly by springs 30 enabling it to recede somewhat with reference to the innermost member when the pawls 26 come into operation. The purpose of this package forming member is to effect the main pressing operation and to hold the blank while the pawls come into action in setting the end walls of the packet as described.

The third or outermost member 31 of the plunger is arranged to slide over the packet forming member and engages the blank just about the edges of the pocket for the purpose of pressing down and creasing the flap portions 32 of the blank whereby the body of the package is left open to receive its contents.

After being shaped by the plunger A the packet or cover is conveyed by reason of the intermittent motion of the chain 1 to appropriate stations to receive the booklets or other insertions and to undergo the various folding and gumming operations required in closing the same.

The booklets of cigarette papers 33 are fed to the packets from a magazine disposed transversely of the machine and terminating at a point 45 just above the centre line along which the chain 1 runs. The magazine comprises a sloping channel way 35 down which the booklets are conveyed by an endless band 36 forming the floor of the channel, the channel way leading in turn to 50 a curved chute 37 which terminates just short of a platform 38 disposed just above the line of motion of the packets carried by the chain 1, see Figures 4, 5 and 6. In the example illustrated it is understood that the machine is arranged for packing the booklets singly, but in the event of it being required to pack booklets in double packets a second booklet magazine disposed symmetrically with reference to that shown in Figure 5 would also be provided, the chutes 60 37 of the two magazines terminating adjacent one another over the platform 38.

The booklets are removed from the platform 38 and transferred to the formed packets in a two stage operation by the aid of a stepped 65 pusher 39 which slides over the platform 38. The pusher 39 receives its motion from a lever 40 which is urged positively in one direction by a rotary cam 41 and returned in the other direction by a spring 42. The operative end of the 70 pusher which has a thickness approximating that of the booklets to be packed extends under the open end of the chute 37 whereas the main portion of the pusher is of greater thickness thereby presenting a step or shoulder 43 which during 75 each stroke of the pusher projects one booklet

to a position beyond the confines of the chute where the said booklet is held against return movement by the action of a vertically reciprocating stop plate 44 timed to descend and become operative during the withdrawal of the pusher 39. The booklet therefore is left flat upon the platform 38 until the next advancing movement of the pusher when it is engaged by the extremity of said pusher and projected into the formed package awaiting adjacent the end of the platform 38.

As the pockets on the chain approach the point where the booklets are inserted the main cover flap of each package projects to one side and passes beneath a guide plate 45 where a detector device is furnished to ensure that each pocket is properly furnished with a formed package before a booklet is delivered to the said pocket. This detector comprises a feeler or finger 46 carried by a lever 47 and arranged to be moved towards and from an aperture in the guide plate 45 by means of a spring 48 and a rotary cam 49 respectively. Prior to arriving at the booklet filling station each platform 21 stops adjacent this detector and if a pressed package is present the feeler on rising will encounter the main flap and restrain the lever from following fully the depression in the cam 49, and so permit but little movement of a stop rod 50 which is connected to the lever 47. Alternatively if the flap is absent the extent of movement of the lever 47 will be determined solely by the form of the cam and will therefore enable the stop rod 50 to interrupt temporarily the operation of the booklet delivery means. Referring again to Figure 4 it will be seen that a bar 51 connected with the lever 47 is slotted longitudinally at 52 where it engages a guide stud 53. Normally the stop rod 50 has no influence upon the bar 51, because under proper working conditions the movement of the stop rod is almost negligible. The lifting of the feeler 46 is however synchronised with the forward thrust of the pusher 39 and in the event of there being no package flap present to intercept the feeler the stop rod 50 will be projected into the slot 52 in the bar 51 and thus arrest the return motion of the pusher causing the booklet delivery mechanism to be inactive during the next cycle of operation. During the next cycle however the stop pin 50 is released from the slot 52 in the bar 51 by the action of the cams 49 and 51 and provided a formed package is present in the next pocket, the pusher will resume its operation and the delivery of booklets.

After being filled with booklets the packages are arrested at various other stations where operations such as the insertion of a stiffening card if desired, the folding and gumming of the flaps and the closing of the package are successively performed but since these features form no essential part of the present invention the mechanisms concerned are not illustrated or described in detail.

However after the completion of these folding and gumming operations the packets pass beyond the ends of the guide plates 23 to a position opposite a pusher 55 arranged on one side of the machine and arranged to operate in ejecting the made up packets laterally from the pockets on the conveyor chain. In line with this pusher but disposed on the opposite side of the machine is a receiver device see Figure 7 comprising a rotary member 56 having four equally spaced holders 57 adapted to accommodate the made up packets, these holders successively coming into

line with the pusher 55 as the member is subjected to an intermittent rotary motion, a quarter revolution at a time. It should be understood that at this stage of the operation the packets 5 are filled and closed but the cover flaps remain in an open or extended condition and the slot through which the cigarette papers are to be extracted lies on the underside of the packet. After being transferred from the conveyor chain to the rotary member the succeeding rotation through a quarter turn of the rotary member brings the packet to a vertical position where the slotted front of the packet may be seen and inspected by the operator in charge. Moreover while the packet is retained in this position a suction nozzle 70 carried upon an oscillating arm 71 enters the slot in the front of the packet and on receding again extracts the free edge of the first leaf or sheet. Following this action the rotary member 56 turns another quarter revolution bringing the said packet once more to a horizontal position but this time inverted, and during this turning the cover flap is partly folded about the packet by engagement with a curved plate 58. Having arrived at this point the packet is ejected from the holder in the rotary member 56 by suitable means and delivered to a plate 59 where the folding down of the cover flap is completed and the package is subjected to a final pressing by an oscillating presser plate 60.

The packet remains on this platform until the ejection of a subsequent packet causes it to be pushed into a magazine 61 where the completed packets are collated on edge ready for removal 35 from the machine as and when required.

I claim:

1. In a machine of the character set forth for packaging booklets of cigarette papers and the like, an intermittently moving conveyor, platforms carried by the conveyor and having ledges across their tops at the leading and trailing ends thereof, and spaced fixed guide bars overlying the side edges of the platforms and coacting with the edges to form pockets within which wrappers for the packets are formed.
2. A machine of the character set forth in claim 1, wherein the ledges carried by the platforms are adjustable relative one to another.
3. A machine of the character as set forth in claim 1, wherein the ledges carried by the platforms are under-cut at their adjacent sides.
4. A machine of the character as set forth in claim 1, wherein the said spaced guide bars are relatively adjustable for the changing of the widths of the pockets for the formation of packet wrappers of different sizes.
5. In a machine of the character set forth for packaging booklets of cigarette papers and the like, a conveyor, platforms carried by the conveyor and each having a ledge across the top side at the leading and trailing edges thereof, spaced fixed guide bars overlying the side edges of the platforms and coacting with the ledges to form pockets within which packet wrappers are formed, said ledges being under-cut in the opposing sides thereof, and means designed to press into the pocket and into the under-cut sides of said ledges thereof, a portion of a blank disposed over the pocket.
6. A machine of the character set forth in claim 5, in which said pressing means includes means for pressing down portions of the blank lying outside the pocket and forming folding flaps for the packet wrapper.
7. A machine of the character set forth in

claim 5, with means functioning subsequent to the formation of the packets in the pockets to introduce a booklet of papers into the packet.

8. In a machine of the character set forth for packeting booklets of cigarette papers and the like, means forming a relatively shallow packet forming pocket, and means for pressing into and forming a packet wrapper from a blank placed over the pocket, comprising a plunger having a portion formed to enter the pocket to press the blank thereinto, and an outer portion movable relative to the first portion for creasing and pressing down flaps forming portions of the blank at the outer sides of the pocket.

9. In a machine of the character set forth for packeting booklets of cigarette papers and the like, means providing a relatively shallow packet forming pocket, said pocket having two opposed walls under-cut, and means for pressing into the pocket a wrapper blank disposed over the pocket, comprising a plunger having a portion adapted to enter snugly into the pocket to press the wrapper blank thereinto, a second portion lying within the first portion and comprising laterally movable members adapted to press a part of the wrapper blank into the under-cut areas of the said opposed walls, and means lying outside the first portion for pressing down and creasing flap forming portions of the blank.

10. In a machine of the character set forth for packeting booklets of cigarette papers and the like, means providing a relatively shallow packet forming pocket having two opposed walls under-cut, and means for pressing into the pocket and forming a packet from a blank disposed over the pocket, comprising a plunger having a central portion movable into the pocket and including a pair of pivoted thrust members designed to spread outwardly to force portions of the wrapper blank into the under-cut areas of the opposed walls, an intermediate portion shaped to snugly enter the pocket to impart to a portion of the wrapper blank the shape and out-line of the pocket, and an outer portion encircling and movable relative to the intermediate portion for pressing outwardly and creasing portions of the blank remaining outside of the pocket and functioning as closure flaps.

11. A machine of the character set forth in claim 10, in which positive thrust movement is imparted to the inner and outer portions of the plunger, and spring members interposed between the intermediate and outer portions of the plunger to urge movement of the intermediate portion relative to the outer portion in the direction of movement of the plunger.

12. In a machine of the character set forth for packeting booklets of cigarette papers and the like, means for providing a shallow open pocket designed to have pressed thereinto a wrapper blank comprising a body portion and foldable flaps, means for pressing into the pocket a blank disposed over the pocket to form a pocket which is designed to receive a paper booklet, means for detecting the absence of a packet from a pocket, and a booklet supply checking mechanism actuated by the said detecting means upon detection of the absence of a packet from the pocket.

13. In a machine of the character set forth for packeting booklets of cigarette papers and the like, means providing a plurality of forming pockets, means for intermittently moving said pockets along a predetermined path, means for depositing a wrapper blank over each pocket at

one stationary position thereof, means functioning at a succeeding stationary position of the pocket for pressing a part of the blank into the pocket to form a paper booklet receiving packet, said formed packet having flaps remaining outside the pocket, an apertured plate adjacent the path of movement of the pocket, one of the flaps moving beneath the apertured plate, a feeler finger adapted to move upwardly through the aperture of the plate and to be arrested in its motion by a flap overlying the aperture, and means actuated by said finger upon movement of the finger through the aperture of the plate in the absence of a packet flap across the aperture for preventing the deposit of a booklet in said packet.

14. In a machine of the character set forth for packeting booklets of cigarette papers and the like, an intermittently movable conveyor, means providing a plurality of packet wrapper receiving pockets carried by the conveyor, means for depositing a packet wrapper blank over each pocket as the pocket comes to a predetermined position of rest, means for pressing a part of the wrapper into the pocket to form a paper booklet receiving pocket, and means movable transversely of the conveyor for successively removing the formed packets from the pocket at a predetermined stationary position of the conveyor.

15. In a machine of the character designed for 30 packeting cigarette paper booklets in wrappers having window openings through which the papers are adapted to be drawn, an intermittently movable conveyor carrying a series of platforms, said platforms having under-cut ledges formed 35 across the top surfaces at the leading and trailing edges thereof, guide plates disposed upon opposite sides of the platforms throughout a portion of the path of travel thereof and cooperating with said ledges to form pockets, over which 40 a windowed wrapper blank is disposed at a predetermined position of the conveyor, means for pressing a position of the wrapper into the pocket to form a booklet receiving packet having two opposite sides engaged under the under-cut portions of the ledges, means operating transversely of the conveyor between said ledges at a position beyond the guide plates to remove a completed packet from the pocket, a rotatable receiver into which the packet is shifted from the platform for inverting the packet to turn the window upwardly, and means for removing the packet from said receiver.

16. A cigarette paper booklet packeting machine of the character set forth in claim 15, with means operating during the time that said receiver receives the packet and inverts the packet to turn the window upwardly for inspection, to extract through the window opening a portion of a paper of a booklet.

17. In combination in a machine for packeting cigarette papers, an endless carrier, a plurality of platforms carried by the carrier, each of said platforms having two transverse ledges upon its top surface, the ledges extending transversely to the line of movement of the platform and having their adjacent sides under-cut, means forming guide plates longitudinally of the major portion of the length of the top run of the conveyor forming guide plates in the plane of the ledges of the platforms and cooperating with the ledges to provide wrapper receiving and shaping pockets, the platforms at one end of the conveyor moving from between the guide plates, means adjacent the other end of the conveyor for depositing wrapper blanks over the pockets, means for

11

pressing the wrapper blanks into the pockets and into the under-cut sides of the ledges to secure the formed blanks in the pockets, means for testing for the presence of a formed blank in each pocket, means operating subsequent to the operation of the testing means for depositing a booklet of papers in each formed pocket, said testing means and said booklet depositing means being operatively coupled together and said testing means functioning to prevent the deposition of a booklet in a pocket in the absence of a wrapper therein, and means operating transversely of each platform between the ledges thereof when the ledges have advanced beyond the guide plates, to effect removal of a formed packet from between the ledges.

18. In a cigarette paper packeting machine including a conveyor and means for enclosing a paper booklet in a packet carried on the conveyor, the packet having a window opening, means movable transversely of the conveyor for removing the booklet carrying packet from the conveyor, a rotary receiver disposed to receive said packet upon removal from the conveyor and comprising a plurality of arms extending radially with respect to the axis of rotation of the receiver, said arms moving transversely of the path of movement of the conveyor, means for successively bringing the ends of the arms into a position of rest in the plane of movement of the packet as the packet is removed from the conveyor, to receive said packet, each of said arms at its outer end comprising a pair of resilient fingers between which the packet is engaged, a suction means,

10

5

15

20

25

30

12

means for bringing the packet carried by an arm into a position adjacent to the suction nozzle for the partial extraction of a paper of the packet through the window opening thereof, and means for removing the packet from its supporting arm when the packet has been moved by the receiver away from said suction means.

19. In a cigarette paper booklet packeting machine including means for conveying along a pre-determined path, a paper booklet containing packet having a window opening and having an unclosed flap, means movable transversely of the conveyor to shift the booklet containing packet laterally from the conveyor, a rotary receiver disposed at one side of the conveyor and having a plurality of arms extending radially with respect to the axis of rotation of the receiver, each of said arms at its outer end comprising a pair of resilient fingers and said arms moving transversely of the path of movement of the conveyor, means for successively bringing the fingers of the arms into a position of rest in the plane of movement of the packet from the conveyor to receive the packet between said fingers, a suction means, means for bringing the suction means and a packet carried by an arm into cooperative relation to facilitate the partial extraction of a paper packet through the window opening, means operating upon the turning of the receiver subsequent to the operation of the suction means, for folding said flap, and means for removing the packet from its supporting arm.

GEORGE DANIEL HORGAN.
